UNITED STATES PATENT OFFICE.

SHELDON S. HARTSHORN, OF ORANGE, CONNECTICUT.

MANUFACTURE OF BUCKLES.

Specification forming part of Letters Patent No. 11,892, dated November 7, 1854; Reissued May 26, 1868, No. 2,955.

To all whom it may concern:

Be it known that I, SHELDON S. HARTSHORN, of the town of Orange, in the county of New Haven and State of Connecticut, 5 have invented a new and useful Improvement in the Manufacture of Buckles; and I do hereby declare that the following is a full, clear, and exact description of the construction, character, and operation of the 10 same, reference being had to the accompanying drawings, which make a part of this specification, in which—

Figure 1 is a perspective view of the buckle, as finished. Fig. 2, is a perspective 15 view of the wire frame of the buckle, when properly formed. Fig. 3, is a perspective view of the tongue part of the buckle ready to be attached to the frame. Fig. 4, is a perspective view of that part of the buckle 20 to which the standing part of the strap is to be attached.

My improvement consists in making the buckle of one piece of wire, and two pieces of sheet metal, by cutting, and forming each 25 piece or part, by a proper die, or swage, and then connecting the three parts, and finishing the buckle with another die, or swage, suited to close the sheet metal parts around one bar, or side, of the frame, so as to make a neat, 30 and durable buckle at small cost.

I make the main frame of the buckle of one piece of wire to form the four sides, as represented in Fig. 2, the two ends of the wire (without dovetails, bosses, or any other 35 preparation) meeting at the center of one of the long sides, as seen at *a*, Fig. 2. I make the tongue part of sheet metal, by cutting and raising it with a proper die, or swage to the shape represented in Fig. 3. I make 40 that part of the buckle to which the standing part of the strap is attached, also, by cutting and raising it, with a proper die, or swage, to the shape represented in Fig. 4. I then pass the partially formed socket *b* of the tongue 45 part, Fig. 3, onto the central part of the open side, *a*, of the main frame, Fig. 2, and the partially formed socket *c*, *c*, of the part

represented in Fig. 4, onto the two extremities of the open side of the main frame, outside of the tongue part; and then, with a 50 proper die, or swage, I set down the edges of the socket portions of Figs. 3 and 4, so as to form a complete socket, (without brasing or soldering,) around that side of the main frame, Fig. 2, extending its whole length, 55 when the buckle will be completely finished, as represented in Fig. 1.

The advantage of my improvement consists in making a very serviceable, as well as cheap, buckle, by making the four sides 60 of the main frame of one piece of wire, and securing the two ends of that wire by the socket of the tongue part of the buckle, while that part to which the standing part of the strap is to be attached will also have 65 a free motion, independent of the other parts.

I am aware that the frame, or bow, of the buckle has been made of one piece, and the ends secured together by bosses, or bulbs on 70 the ends, and the socket part of the tongue made to fit them, as made by P. P. R. Hayden, and, also by dovetailing the ends together, and securing the dovetailed ends by the socket part of the tongue, as made by 75 Wm. Shove, (neither of which is used by me in the manufacture of my buckle). I, therefore, do not claim either of them as my invention, but distinctly disclaim them; but

What I claim as my invention, and desire 80 to secure by Letters Patent, is—

The manufacture of a buckle of three parts, by dies, or swages, in such manner that the two ends of the wire, of the main frame, shall be secured by the socket of the 85 tongue part, while the other part will have a free, independent motion, when the whole is constructed, and fitted for use, substantially, as herein described.

SHELDON S. HARTSHORN.
